RAILWAY TELEGRAPH.

No. 591,339.

Patented Oct. 5, 1897.

UNITED STATES PATENT OFFICE.

ALBERT C. FRIESEKE, OF FLORAL BLUFF, FLORIDA.

RAILWAY-TELEGRAPH.

SPECIFICATION forming part of Letters Patent No. 591,339, dated October 5, 1897.

Application filed November 20, 1895. Serial No. 569,522. (No model.)

To all whom it may concern:

Be it known that I, ALBERT C. FRIESEKE, of Floral Bluff, in the county of Duval and State of Florida, have invented an Improved Railway-Telegraph, of which the following is a specification.

This invention is an improved railway-telegraph, the object being to provide a telegraph system whereby a series of trains are arranged in electric communication with the central or despatcher's office, so that messages can be sent from the central or despatcher's office to any train or from any train to the central or despatcher's office.

Another object is to provide a telegraph system in which only the train communicating or communicated with will be in communication with the central or despatcher's office, thus avoiding numerous complications.

Another object is to provide a railway-telegraph in which there are independent message and bell circuits to the common return line or conductor.

Another object is to provide a railway-telegraph in which the circuits are normally open, thus economizing in the use of batteries; and still another object is to provide a railway-telegraph in which the ordinary line-battery of a permanent telegraph may be used at the central office instead of a separate or special battery; and the still further object is to provide a railway-telegraph which depends upon direct contact, and thus employs a well-known principle in contradistinction of railway-telegraphs operating upon the principle of induction.

With these various objects in view my invention consists in a peculiar construction and arrangement of the various parts, all of which will be fully described hereinafter and pointed out in the claims.

In the drawings forming a part of this specification, Figure 1 is a perspective view showing a car provided with suitable telegraphic instruments, the trolley, and the conductor-wires used in my improved telegraphic system. Fig. 2 is a detail diagrammatic view of the central or train-despatcher's office, showing the connection of the various wires with the local bell and sounder circuits. Fig. 3 is a similar view showing the arrangement em-

ployed in a car. Fig. 4 is a detailed view of the relay and its connections. Fig. 5 is a detailed view of the trolley, and Fig. 6 is a detailed view of the supporting-bracket.

55

In carrying out my invention I preferably employ three conductors or wires A', B', and C', said wires being preferably suspended above the line of railway-track by means of suitable hangers D, which hangers may be attached to a cross-bar E, supported by poles F, or said hangers may be attached to an arm E', projecting laterally from the single post F', this latter structure being preferred, inasmuch as it is more economical. The conductor or wire A', I shall denominate the "bell-wire," the wire C' the "message-wire," and the conductor or wire B' the "common" or "neutral" return-conductor, said conductor or wire B' serving as the return-wire in both bell and message circuits, as more fully explained farther on.

The battery G is connected with the conductor B; but, if desired, the main battery of a permanent telegraph may be used in this connection without serious inconvenience, inasmuch as the circuits of my device are normally open, and the delay will occur in the use of the permanent telegraph only during the period that the message is being sent over my railway-telegraph system, a loss of time so small as can scarcely be appreciated.

The wires or conductors A and C are connected to the binding-posts H and I, respectively, of a switchboard K, said switchboard being provided with the lever L, pivoted at the end M upon a connecting-post N and provided at its opposite end with the contact-point O, whereby said lever can be connected to either the binding-post H or I and connect either the bell or message wire with the relay R by means of the wire P.

B¹ indicates the electric bell; B², the local battery; B³, the local-circuit wires connecting the relay and bell with the switchboard T.

95

S indicates the sounder of usual construction, S² the local battery, and S³ the local-circuit wires connecting the relay and sounder with the switchboard T. The switchboard T is connected to the relay by means of a wire or conductor U, and is provided with the switch-lever V, having a contact-point

adapted to be moved into contact with the points W and X to close the bell and sounder circuits, respectively.

K' indicates the key, which is connected 5 with the relay by means of a wire or conductor K² and with the main or line battery by means of a conductor or wire K³.

The apparatus as above described is clearly 10 illustrated in Fig. 2, and in Fig. 3 I have shown a similar apparatus which is used upon the car of a train, said apparatus being represented as somewhat smaller than that of the main or despatcher's office; but the arrangement and construction of the various 15 parts are exactly the same; but for further discrimination I have indicated the parts of Fig. 3 by the small letters instead of by capitals, as in Fig. 2.

In Fig. 4 I have shown a detailed view of 20 the relay and the conductor-wires extending over the same, thus clearly indicating the manner in which said relay operates to close the different circuits of the bell and sounder.

Now in operation an apparatus such as I 25 have described is located in the central or train-despatcher's office and the conductors A, B, and C connected with the overhead conductors or wires A', B', and C', respectively.

A trolley-pole 1 is mounted upon the top of 30 the baggage-car, said pole being preferably tubular in form, and at its upper end is provided with three arms 2, 3, and 4. The central arm 3 is preferably integral with the pole 1, and the arms 2 and 4 are attached to lugs 35 5, extending laterally from said pole, said arms 2 and 4 being properly insulated from the pole and central arm by means of an insulating-strip 6, bushings 6^a, and washers 6^b, so that currents are always insulated from 40 each other.

The bell wire or conductor a is connected to the arm 2, and the message wire or conductor c is connected to the arm 4, the common return-wire b being connected with the 45 pole 1 and arm 3, and when said trolley is in contact with the overhead wires it will be understood that the arms 2, 3, and 4, carrying contact-wheels 2^a, 3^a, and 4^a, respectively, will bear upon the under sides of the wires or 50 conductors A', B', and C', respectively, thus connecting the wires A', B^b, and C' of the main line and A, B, and C of the central office with the wires or conductors a, b, and c of the train or conductor's instrument.

55 The arms 2, 3, and 4 are preferably constructed of elastic metal, so that said arms are always held positively in contact with the overhead wires, and by this arrangement all irregularities or unevenness of the tension of 60 conductor-wires will be compensated for, and in order to prevent the contact-wheels slipping off the overhead wires I construct the upper end of each arm with fingers, whereby any lateral movement of the trolley will be prevented. It is obvious that the central arm and wire B' could be dispensed with and connection made with one of the rails through

the wheels of the car. Wherever economy in construction would play an important part this modification would probably be adopted. 70

Now in practical operation the train-despatcher normally has his switch-lever L in contact with the post I and switch-lever Y in contact with post W, so that when a connection is made on one of the trains between B' 75 and C' he will be signaled on his bell. All of the train-operators normally have their switch-levers l on the posts h and their lever v on the posts w, so that when the train-despatcher makes connection between the wires 80 A' and B' all of the train-operators are signaled. These connections are made in the following manner: When a train-despatcher desires to communicate with train No. 5, he opens his key K', throws his switch L to point 85 H, presses his key five times, returns his switch to point I, and closes his key. The train-operator on train No. 5 having heard his call, waits long enough for the despatcher to make the above changes, then opens his key 90 k', throws his switch l to point i, presses his key five times, indicating to the despatcher that the call has been received by the proper operator, and then both despatcher and operator respectively throw their switches V and 95 v to points X and x, when they are in position to communicate in the usual manner. On finishing their conversation they return their instruments to their normal position, and the other train operators have heard nothing but 100 the five rings given by the despatcher in calling the operator.

When a train-operator desires to call up the despatcher, he opens his key k', throws his lever l to point i, depresses his key a number 105 of times until the despatcher opens his key, which is indicated to the operator by the fact that his own key fails to close the circuit, when both operator and despatcher respectively change their levers v and V to points 110 x and X. As in the other case, they return their instruments to their normal condition when through using them, and in this case the other operators have heard nothing whatever. 115

While I have shown and described this apparatus as arranged in the baggage-car, it is obvious that it can be arranged in any car, or supplemental devices could be arranged in each and every car, and, furthermore, while I have described my telegraph as particularly adapted for establishing communication between a train despatcher and conductor for railway purposes it will of course be understood that my telegraph could also be employed for the transmission of commercial or private messages of the passengers upon the train. 125

If desired, a telephone instrument could be used in place of a telegraph-key, and in order to prevent any possible breakage of current the contact-wheels could be made in the form of brushes. 130

Having thus described my invention, what

I claim as new, and desire to secure by Let-
ters Patent, is—

1. In a telegraph or like system, three con-
ductors, stations connected to said conduc-
tors, each containing a two-point switch hav-
ing its points connected to two of the con-
ductors, receiving and transmitting instru-
ments, wires connecting said instruments to
the lever of the switch and the third con-
ductor, and an electric generating device con-
nected to said third conductor, substantially
as described.

2. In a telegraph system, three conductors,
stations connected to said conductors, each
containing a two-point switch having its
points connected to two of the conductors, a
relay and key, wires connecting the relay and
key together and to the lever of the switch
and the third conductor, an electric-supply
source connected to the third conductor, a
second two-point switch having its lever con-
nected to one of the contact-points of the re-
lay, a bell and battery connected between one
of the points of the second switch and the
other contact-point of the relay, and a sounder
and battery connected between the other
point of the second switch and the second-
named contact-point of the relay.

3. In an electric railway, three conductors
extending along the railway-track, trolleys
carried by the cars having three trolley-arms

connected thereto and insulated from each
other, a trolley-wheel journaled in each trol-
ley-arm and adapted to travel in contact with
one of the conductors, a set of instruments 35
carried by each car consisting of a two-point
switch having its points connected to two of
the trolley-arms, receiving and transmitting
instruments connected to the lever of the
switch and an electric-supply source con-
nected between the instruments and the third
trolley-arm, substantially as described.

4. In a railway telegraph or telephone sys-
tem, a main station and substations carried
by trains, three wires connecting said stations,
45 a set of instruments in each station, the in-
struments of the main station being connected
to the first and second wire, the instruments
of the substations being connected in multi-
plicity to the second and third wires, a switch at 50
the main station to throw the instruments of
that station in connection with the second
and third wires, and switches in the substa-
tions to throw their instruments in connec-
tion with the first and second wires. 55

In testimony whereof I affix my signature
in the presence of two witnesses.

ALBERT C. FRIESEKE.
